LIFE BOAT LAUNCHING APPARATUS

Original Filed Feb. 12, 1919

Fig. 1.

INVENTOR,
John L. Hyland

UNITED STATES PATENT OFFICE

JOHN L. HYLAND, OF NEW YORK, N. Y.

LIFE-BOAT-LAUNCHING APPARATUS

Refile of abandoned application Serial No. 276,554, filed February 12, 1919. This application filed November 23, 1928. Serial No. 321,526.

This application is refiled for abandoned application Serial No. 276,554, filed February 12, 1919, and the invention relates to certain new and useful improvements in a life boat launching apparatus, and especially to an improved skid for supporting and holding a boat as it is lowered down the side of a ship and launched.

The principal object of this invention is to provide an endless cable or chain runner having a portion extending over the skid surface to hold the latter off from the side of a ship so that no skid action occurs, the cable runner sliding over the skid and preventing the marring of the side of the ship.

The invention further resides in the features of construction and arrangements and combinations of parts, hereinafter described and claimed, reference being had to the accompanying drawing, wherein

Fig. 1 is a fragmentary sectional view of a life boat showing one embodiment of the invention;

Fig. 2 is an outside elevation thereof;

Fig. 3 is a view of a modified form of skid applied to a life boat, and

Fig. 4 is an outside elevation thereof.

The boat 1 may have the skid passing entirely thereabout as depicted in Fig. 1 or only to one side thereof as shown in Fig. 3, or the skid may be permanently fastened to the boat.

In the form depicted in Figs. 1 and 2, the skid 2 has its outer frame member 3 provided with a plurality of openings 4 in which are journaled pulley wheels 5, the short shafts supporting the wheels being mounted in the cross braces 6 which space the inner and outer frame members of the skid.

An endless chain rope or cable 7 is passed through the braces 6 and pulley wheels and over the outside of the skid to hold the latter off from the side of the ship. The cable is wound once around the center pulley so as to hold the same thereon and in practice as the skid and life boat are being lowered down the side of a ship, the cable will engage the latter while the skid slides over the cable. On the upper end of the skid is mounted a large

roller 8 to further facilitate the lowering operation.

The form of skid disclosed in Figs. 3 and 4 is designed to seat on one side of a life boat, the same being fastened thereto by a chain 9 which passes entirely about the boat from a bracket arm 10 that engages over the upper edge of the side of the boat.

The endless cable 11 is in this instance mounted on pulley wheels 12, journaled on one side of the skid, said chain passing through openings in the side of the skid and coming out on the skid surface thereof to present a rest 13 over which the skid will slide on the side of a ship.

On the lower end of this skid are mounted a pair of rollers 14 on different axes which are elevated one above the other to facilitate their passage over any obstruction in the path of the skid as it is moved about on the ship.

In fire drills on a ship the boat launching skids are lowered and raised over the side of the ship so that the surface would steadily become marred and then the skid may encounter some obstruction. The endless cable acts to lay a track or tread on the side of the ship for the skid to travel thereover. This endless cable prevents injury to the side of the ship and also makes the launching operation safer.

This application is an improvement on my application, filed Sept. 17, 1917, bearing Ser. No. 191,853 on Boat launching apparatus, now Patent 1,304,816, May 20, 1919.

What is claimed is:—

1. A boat launching apparatus comprising a skid constructed to receive and hold a boat, pulley wheels journaled on the skid, and an endless cable passing about the pulleys and over the outer face of the skid.

2. A boat launching apparatus comprising a skid constructed to receive and support a boat, an endless chain passing over the outer face and thence guided through the skid, and pulley wheels over which the cable takes.

3. A boat launching skid having a plurality of pulleys journaled to its side and an endless cable passing over the pulleys and through the skid and over the outer face there-

of to hold the skid off from the side of a ship.

4. A boat launching skid shaped to receive a boat and an endless cable running over the outer face of the skid and supported by pulleys.

5. A boat launching skid comprising a curved skid body, and an elongated endless runner member operating over at least a section of the outer surface of the skid body.

10 6. A boat launching skid comprising a curved skid body, an elongated endless runner member operating over a section of its convex area, and a wheel spaced from the runner member and arranged at the upper end of the body and projecting beyond the convex face thereof.

In testimony whereof I affix my signature.

JOHN L. HYLAND.
